UNITED STATES PATENT OFFICE.

EDMUND H. LUNKEN AND HENRY RITTER, OF CINCINNATI, OHIO, ASSIGNORS TO THE
LUNKEN STEEL WINDOW CO., OF CINCINNATI, OHIO.

WINDOW CONSTRUCTION.

No. 902,980.

Specification of Letters Patent.

Patented Nov. 3, 1908.

Application filed May 9, 1908. Serial No. 431,986.

To all whom it may concern:

Be it known that we, EDMUND H. LUNKEN and HENRY RITTER, citizens of the United States, residing at Cincinnati, Ohio, have invented certain new and useful Improvements in Window Construction, of which the following is a specification.

Our present invention relates to improvements in window construction and is designed as an improvement upon the form of window which forms the subject of an application for Letters Patent of the United States, filed on the 8th of February, 1908 by Edmund H. Lunken and Charles M. Conklin; Serial No. 415,446.

Among the objects of the present invention are to improve the window in various details or features of construction with a view to increased simplicity and durability and economy in manufacture.

The invention includes the features of construction and arrangement and combination of parts hereinafter described and particularly set forth in the appended claims.

The invention is illustrated in the accompanying drawings, in which:—

Figure 1 is a front elevation of the improved window. Fig. 2 is a transverse section on line 2—2 of Fig. 1, but on a larger scale. Figs. 3 and 4 are enlarged sectional elevations showing more in detail the manner of supporting the guide bar and illustrating also the guide bar in its two different positions. Fig. 5 is a transverse sectional view showing the invention as embodied in a wooden window casing.

Referring by reference characters to this drawing, the numeral 1 designates the window frame or casing and 2 the window sashes. Each side of the window frame is provided with two outer channels 3 and a central or intermediate channel 4 these channels being formed as integral parts, by pressing or stamping, in the removable cover or facing plate 1^a of the frame or casing.

The sashes are supported by sash cords 5 designed to be counterbalanced by weights 6 in the usual manner and as the counterbalancing forms no part of the present invention, a more specific description thereof is deemed unnecessary. It suffices to say that the sash cords are connected to eye pieces 7 in which are journaled the hinge pintles 8 upon which the sash frames hinge or pivot, the eye pieces moving vertically in the chan-

nels 3 as the sashes are raised and lowered. The means for guiding the sashes in their vertical sliding movement comprises bars 9 which are located on opposite sides of the window frame and are provided with ribs 9^a and 9^b, which are adapted to engage with corresponding grooves or channels in the side edges of the upper and lower sash respectively. These guide bars or members extend continuously and unbroken from the bottom of the window frame to the top and form an unbroken guide for the sashes. Each guide bar is preferably constructed of non-corrosive metal stamped or pressed into the desired shape. The walls which form the ribs 9^a and 9^b are parallel with a space between in which snugly fit the thin intervening webs 1^b between the channels 3 and 4, which webs are formed by the folding or doubling of the metal of the cover plate in the process of manufacture of the same. The guide bars normally project into the position shown in Figs. 2 and 3, and in such position serve to guide the sashes in their vertical movement and of course prevent their being swung upon the hinge pintles 8. When it is desired to swing either of the sashes for the purposes of cleaning or ventilation, the guide bars are moved laterally away from the sash to remove the ribs 9^a and 9^b from engagement with the grooves or channels in the edges of the sash.

We prefer to construct and arrange the guide bars so that they will be automatically held by gravity in engagement with the sashes so that they can be removed from engagement therewith by simply lifting them and imparting a slight lateral swing to the lower ends whereby they will be automatically locked in their elevated and disengaged position by gravity. To accomplish this a reinforcing bar 10 is provided which is secured to the portion 9^c of the guide bar between the guide ribs. This reinforcing bar is preferably made of solid metal and serves to strengthen or stiffen the guide bar, enabling the latter to be made of a minimum amount of comparatively thin non-corrosive metal. Each guide bar is provided near the top of the window frame with an inclined slot 11 through which passes a pin or rivet 12, which has its ends seated in and held by the walls of the channel 4. In each guide bar near the lower part of the window frame is formed an L or elbow shaped slot 13, 110

which is engaged by a pin or rivet 14 held in the manner similar to that described in connection with the pin 12. While we prefer to have the slots in the reinforcing bar 5 and the pins secured to the webs of the casing, it is evident that the construction may be reversed, by placing the slots in the webs of the casing and securing the pins in the reinforcing bars and thereby attain the same 10 results.

Normally the guide bar and its reinforcing bar will occupy the position shown in Fig. 3, in which the pins 12 and 14 will rest in the upper ends of the slots 11 and 13 15 respectively, being so held by the weight of the bar, the inclination of the slot 11 at the upper end causing the bar to be pressed outwardly. When, however, it is desired to move the bar inwardly to disengage the bar 20 from the window sash or sashes to permit the same to be swung upon their horizontal pivots, it is only necessary to raise the guide bar until the pin 14 has reached the bottom of the vertical portion of the L or elbow 25 shaped slot. During this movement the engagement of the pin 12 with the inclined slot 11 will cause the upper end to move laterally and the lower end may be swung horizontally outward and cause the pin 14 to rest in 30 a horizontal portion of the L or elbow shaped slot, at which time the guide bar will be locked in its elevated and disengaged position by gravity. The lower L or elbow 35 shaped slot 13 in each bar is preferably formed by simply cutting in to the rear side of the bar, while the upper slot 11 is formed by cutting in from the front side of the bar, both slots thus opening the one to the front side of the bar and the other to the rear side. 40 In order to hold the pin 14 in the L or elbow shaped slot 13, a strap 15 of sheet metal is applied over the back of the slot, its ends being secured to the reinforcing bar in any desired manner. The lower ends of the 45 reinforcing bars are inclined as shown to correspond with the inclination of the slot 11 and the space at each end formed by this inclination is filled by blocks or filling members 16.

50 In Fig. 5 we have shown how the same construction of guide bar could be applied to an ordinary wooden window frame. In this construction the cover plate 1^b is secured to the wooden window casing 1^a by the beads 55 or strips A and B and if desired, one edge of this plate may be turned up as indicated at b and seated in a groove b' in the strip B for forming a more secure engagement.

Having thus described our invention, what 60 we claim is:—

1. In combination, a window casing, removable cover plates for the sides thereof having two side channels and an intermediate channel with intervening webs sepa-

rating said channels, a guide bar having parts 65 embracing said webs, a reinforcing bar secured to the rear face of the guide bar between said embracing parts, and a window sash or sashes guided by said guide bars and having hinge pintles engaging the side channels, substantially as described. 70

2. In combination, a window frame a cover or facing plate on each side, having a pair of vertical side channels and an intermediate channel, upper and lower sashes 75 having hinge pintles engaging said side channels, guide bars having guide ribs engaging said sashes, a reinforcing bar secured to the rear face of the guide bar, said reinforcing bar having an inclined slot at 80 its upper end and an L or elbow shaped slot at its lower end and pins carried by the cover plate and engaging said slots, substantially as described.

3. In combination, a window frame having 85 in each side member a pair of channels, upper and lower sashes having hinged pintles guided in said channels, guide bars located between said channels and extending the full height of the window casing and 90 having tongue and groove engagement with said sashes, an inclined slot and pin connection between the upper end of each bar and the casing, and an L or elbow shaped slot and pin connection between the lower end of each 95 bar and the casing, substantially as described.

4. In combination, a window frame, upper and lower sliding and swinging sashes having hinge pintles guided by said frame, sheet metal guide bars having a tongue and groove 100 connection with both said sashes, reinforcing bars secured to the outside faces of said sheet metal guide bars, and means for movably connecting said reinforcing bars to the window casing, substantially as described. 105

5. In combination, a window frame having in each side member a pair of channels, upper and lower sashes having hinge pintles guided in said channels, guide bars located between said channels and having tongue 110 and groove engagement with said sashes, an inclined connection between the upper end of each guide bar and the casing to move the upper end of the guide bar upward and outward, and a device simultaneously operating at the lower end of the guide bar, whereby the guide bar when lifted upward and outward at its lower end, is held in such position by force of gravity, substantially as 115 described. 120

In testimony whereof, we affix our signatures in presence of two witnesses.

EDMUND H. LUNKEN.
HENRY RITTER.
